UNITED STATES PATENT OFFICE.

ABBOT AUGUSTUS LOW, OF HORSeshoe, NEW YORK.

SPARKING PLUG FOR HYDROCARBON-MOTORS.

No. 927,255.

Specification of Letters Patent.

Patented July 6, 1909.

Application filed February 20, 1909. Serial No. 479,160.

To all whom it may concern:

Be it known that I, ABBOT AUGUSTUS LOW, a citizen of the United States, residing at Horseshoe, St. Lawrence county, and State of New York, have invented certain new and useful Improvements in Sparking Plugs for Hydrocarbon-Motors, of which the following is a specification.

The object of my invention is to obviate the difficulties and delay heretofore attendant upon adjusting a spark plug into position, either originally or after it has been removed for the purpose of cleaning. This I accomplish by the use of a bushing to which is attached a cylindrical guide sleeve upon and surrounding the sparking plug, which is mounted upon a guiding thread in said sleeve whereby the plug is centralized with relation to the bushing, so that it may be quickly and conveniently inserted therein for the purpose and substantially in the manner hereinafter set forth,—the invention consisting in the specific construction and arrangement of parts described and claimed.

In the accompanying drawings, Figure 1, is a central vertical sectional elevation showing a spark plug provided with my improvements, the plug being shown as inserted in place in the bushing; Fig. 2, is a similar view showing the plug withdrawn from the bushing; Fig. 3, is an elevation of the outer end of the plug provided with my guide sleeve.

C, represents the inner side of the combustion chamber of a hydrocarbon motor of any ordinary or desired construction; W being the water jacket surrounding the same. The walls w, w, of the water jacket W, are tapped to receive a bushing B, having an external flange b, the periphery of which is formed with a male screw thread b', for engagement with the female screw s, on the inner end of the cylindrical guide sleeve S. The cylindrical sleeve S, is also formed with the internal guide screw thread s', for engagement with a male screw thread p, formed upon the periphery of the flange p', of the spark plug P, which latter may be of any ordinary or well known construction, having the facets p², for engagement with a key wrench. Between the threads s and s', is a space s², in the sleeve S, which communicates with the atmosphere through holes or perforations s³.

The sparking plug P, is delivered for use with the guide sleeve S, attached to it, the plug being in the retracted position with rela-

tion to the sleeve as indicated in Fig. 2. In applying the plug for use the sleeve is screwed or otherwise secured to the flange b, of the bushing B, which brings the screw thread p³, on the plug into perfect alinement with the female screw thread b², in the bushing B,—the female guide screw thread s', in the cylindrical sleeve S, acting to guide and centralize the plug with accuracy so that it may be quickly and conveniently inserted or withdrawn from position in the bushing by the use of an ordinary key wrench. The two positions are illustrated in Figs. 1 and 2, of the drawings, in which Fig. 2, represents the position of the plug either before its initial insertion or after it has been withdrawn for the purpose of cleaning, in which latter case the holes s³, perform the function of blow out holes.

The discharge from the cylinder C, of the air and gases under pressure through the space s², and holes s³, in the guide sleeve S, cleans the plug and removes all moisture, soot or sediment that may have collected thereon, the holes s³, not only admitting of this action, but also affording means for admission of a cleansing inrush of pure, clean air after the internal pressure is exhausted.

By my improved construction and arrangement of parts the delay and difficulty heretofore involved in alining the plug and effecting a proper engagement of the male and female screw threads is obviated; while the plug may be effectually cleaned without removing it from position, in one sense of the word, since it is only necessary to withdraw it from the bushing, while still retaining it in its position in the guide sleeve S, and in alinement with said bushing in order to effect this result.

What I claim as my invention and desire to secure by Letters Patent is,

1. In a device of the character designated, the combination of an externally threaded bushing engaging with and extending through the wall of a combustion chamber and formed with an internal screw thread for engagement with a male thread on the spark plug, a guide sleeve attached to said bushing and formed with an internal guide screw thread, and a spark plug formed with the male screw thread for engagement with the female screw thread in the said bushing and with a concentric flange thread peripherally for engagement with the screw thread in the guide sleeve, whereby the threaded lower portion

of the spark plug is centralized for engagement with the female screw thread in the said bushing, for the purpose described.

2. In a device of the character designated, the combination of an externally threaded bushing engaging with and extending through the wall of a combustion chamber and formed with an internal screw thread for engagement with a male thread on a spark plug, a guide sleeve attached to said bushing and formed with an internal guide screw thread and a spark plug formed with the male screw thread for engagement with the female screw thread in the said bushing and with a concentric flange threaded peripherally for engagement with the screw thread in the guide sleeve, whereby the threaded lower portion of the spark plug is centralized for engagement with the female screw thread in the said bushing, said guide sleeve being also formed with holes near its inner end, for the purpose described.

3. In a device of the character designated, the combination of an externally threaded bushing engaging with and extending through the wall of a combustion chamber and formed with a male thread on the spark plug, said bushing being also formed with an external peripherally threaded flange, a guide sleeve formed with a female screw thread engaging the said peripherally threaded flange on the bushing and also formed with an internal guide screw thread, and a spark plug formed with the male screw thread for engagement

with the female screw thread in the said bushing and with a concentric flange threaded peripherally for engagement with the screw guide thread in the sleeve, whereby the threaded lower portion of the spark plug is centralized for engagement with the female screw thread in the bushing, for the purpose described.

4. In a device of the character designated, the combination of an externally threaded bushing engaging with and extending through the wall of a combustion chamber and formed with an internal screw thread for engagement with a male thread on the spark plug, said bushing being also formed with an external peripherally threaded flange, a guide sleeve formed with a female screw thread engaging the said peripherally threaded flange on the bushing and also formed with an internal guide screw thread, and a spark plug formed with the male screw thread for engagement with the female screw thread in the said bushing and with a concentric flange threaded peripherally for engagement with the screw guide thread in the sleeve, whereby the threaded lower portion of the spark plug is centralized for engagement with the female screw thread in the bushing, said guide sleeve being also formed with holes near its inner end, for the purpose described.

ABBOT AUGUSTUS LOW.
